Patented Dec. 12, 1922.

UNITED STATES PATENT OFFICE.

FRANK WENZEL, OF ALEBANY, NEW YORK.

IDENTIFICATION MARKING FOR AUTOMOBILES.

Application filed April 18, 1922. Serial No. 554,927.

To all whom it may concern:

Be it known that I, FRANK WENZEL, a citizen of the United States, residing at Albany, in the county of Albany and State 5 of New York, have invented certain new and useful Improvements in Identification Markings for Automobiles; and I do hereby declare the following to be a full, clear, and exact description of the same, reference being had to the accompanying drawings, forming part of this specification.

This invention relates to a system of marking automobiles so as to destroy the market for stolen automobiles and has for 15 its principal object the provision of a system that may be carried out without undue complications and which will prevent the purchaser of a stolen car from obtaining a license plate from the State authorities provided that the theft of the car has been 20 duly reported.

A further and important object of the invention resides in the provision of the markers per se and in combination with 25 the steering wheel of the automobile.

The number of cars stolen annually is indeed appalling, and while more than half the cars stolen are finally returned to their 30 owners the value of cars stolen and never recovered has reached enormous figures particularly in the metropolitan cities and in the more densely populated sections of States having numbers of relatively large cities separated by only a few hours' travel.

If it were possible to devise some way of preventing the disposal of a stolen car the 35 evil would soon cease, but up to the present time this has been found practically impossible and the present invention relates 40 to the next most logical step, that is, the elimination of the market for stolen automobiles by rendering it impossible for the purchaser of a stolen car to get a clear title to it and his inability to obtain a license 45 plate for the following year.

In the drawings,

Figure 1 is a plan view of a portion of a steering wheel embodying the device of the present invention.

Fig. 2 is a vertical section on line 2-2 of Figure 1.

Fig. 3 is a transverse section on line 3-3 of Figure 1.

Fig. 4 is a sample page from the records 55 of the State authorities.

The device per se is relatively simple,

consisting in a plurality of markers *a*, *b*, and *c* representing together the key number of the automobile as registered by the State authorities, and similar markers *d*, *e*, *f*, and *g* representing together the motor number. If desired the motor number can always be limited to four digits by utilizing only the last four figures of the motor number omitting letters should they form part of the maker's motor number.

The key number is separated from the motor number by a space twice as great or more as the distance between adjacent markers such as *a* and *b*, and it is the intention that the seven bands shall be so located on the steering wheel so that when the car is moving directly forward all seven will be visible to a traffic officer, that is, the bands are centered about the top of the steering wheel when going straight ahead.

The markers are similar and each includes a small strip of copper *h* approximately five-thousandths of an inch thick and any desired width as for example one-half inch or less. On this strip of copper *h* is a numeral *k* positioned within the oval opening *m* in the steel band *n* which encircles the steering wheel *p*. A small sheet of glass *r* approximately $\frac{1}{16}$ of an inch thick is placed between the steel band *n* and the copper strip *h* to protect the latter from injury. The glass *r* (which may be celluloid or any other transparent material) is made thin in order that an attempt to change the number would result in the destruction of the extremely thin strip of copper.

The system of the present invention is as follows: On purchase of a new car the owner presents the bill of sale to the local State authority and is given a license tag and at the same time the State authority enters the owner's name with make of car, motor number, etc., on the regular blank for forwarding to the State capital, and the local State authority or his representative then affixes to the steering wheel *p* bands such as *a*, *b* and *c* representing the key number of the State records and also affixes the bands *d*, *e*, *f*, and *g* which correspond to the number of the motor in the vehicle. These bands are permanently secured to the steering wheel and are not intended to be removed at any time during the life of the car.

If during the year the car should be stolen 110 the thief or the new purchaser would not be able to secure the next year's license tag

for the reason that if he should give a fraudulent key and motor number the discrepancy on the books would be noted at once, and should he give the correct number, reference to the books would disclose that this car had been stolen during the year and the police would be promptly notified.

It is also contemplated to stamp the index or key number on the steering wheel into different parts of the motor in code and preferably by dividing the key number into portions and putting the first two numerals on one part of the motor, the next two on another part, and the next two on still another part of the motor indicating from their position on the motor their value.

Thus if the car were to be stolen and the parts removed and assembled in another vehicle a subsequent inspection necessary before registration would at once indicate that the parts had been removed from another vehicle and by means of the code and the key its subsequent identification might be established.

There are at the present time over eight hundred different makes of motor vehicles operating in the United States, so that if the motor number alone was to serve as an index, eight hundred different indices would be required, but under the method outlined above, only one index is required. The sheet shown in Fig. 4 is a suggested outline showing how the records might be kept. By reference to this sheet it will be seen that in addition to the co-ordination of the two factors, index number and motor number, the make of the car also enters, so that it would be absolutely impossible for a person not the owner to obtain a registration on the car, since if the car were stolen and the thief gave the same information as indicated on this sheet, it would be immediately discovered, because by this method, it is possible to indicate on the record by a simple symbol the theft of any particular motor vehicle. It is also possible by this method to obtain a complete history of any car for any number of years.

In the first column *s* of the chart shown in Fig. 4 is written the number assigned by the registration bureau, in the second column *t* is written the name of the manufacturer of the vehicle, in the next column *u* appears the horse-power of the car this being convenient in many States where the cost of the license varies with the power of the car. In the fourth column *v* appears the number assigned by the manufacturer to the engine or

motor, and in the next columns *w*, *x*, *y*, *z*, etc., appear the license numbers assigned by the State motor vehicle bureau for the particular years indicated in the headings of those columns.

What I claim is:

1. A method for preventing theft of automobiles consisting in applying to the steering wheel of an automobile a plurality of spaced markers, said markers carrying reference characters corresponding with the records of the State authorities. 65

2. A method for preventing transfer of stolen automobiles consisting in the placing on the steering wheel of an automobile in such position that it will be visible to a traffic officer of a plurality of separated bands together denoting a portion of the motor number. 75

3. In combination, a steering wheel, a plurality of separated bands each having assigned to it a value, and a second plurality of spaced bands also having relative values. 80

4. In combination, a steering wheel of an automobile, and a plurality of markers each bearing a reference character.

5. In combination, a steering wheel of an automobile, and a plurality of markers thereon, each marker consisting of a strip partially surrounding the wheel rim and bearing an insignia, and a non-removable protective covering having an opening therein through which said insignia is visible. 90

6. In combination, a steering wheel of an automobile, and a plurality of markers thereon, each marker consisting of an extremely frail strip of material bearing an insignia and partially surrounding the wheel rim, a transparent protective covering therefor, and a closed band of relatively strong material surrounding said protection and steering wheel rim and having an opening 100 in same for viewing said strip through said covering.

7. A band adapted to be permanently secured to an automobile steering wheel, said band including a strip of material directly and permanently secured to the steering wheel, an easily broken transparent protective covering therefor, and a closed metallic band of relatively strong material surrounding said protective covering and having an opening therein for viewing the strip through said protective covering, said strip being of such extreme fragility as to be destroyed by an attempt to remove same, or by the breaking of the transparent covering. 105

FRANK WENZEL.
